UNITED STATES PATENT OFFICE.

SAMUEL B. RIAL, OF TEMPE, ARIZONA.

FAN.

Application filed October 21, 1925. Serial No. 64,011.

This invention relates to improvements in fans for use in frightening and shooing flies from the presence of a person while sleeping, the general object being the provision of an oscillating arrangement used in conjunction with the fan in sweeping a desired space in frightening and shooing the flies therefrom.

Another object of my invention is the provision of a governing apparatus operated by the oscillating apparatus for controlling the speed of the fan so that the noise incident to the operation of the same may not disturb the person asleep.

With the above and other objects in view, the invention further includes the following novel features and details of construction, to be hereinafter more fully described, illustrated in the accompanying drawings and 20 pointed out in the appended claims.

In the drawings:—

Figure 1 is a top plan view of my invention.

Figure 2 is a side elevation thereof.

Figure 3 is a fragmentary top plan view 25 of a portion of the oscillating apparatus.

Figure 4 is a front elevation of my invention as completed.

Figure 5 is a sectional view illustrating a 30 mounting portion of the oscillating apparatus.

Figure 6 is an elevation of a fan used in conjunction with the oscillating apparatus.

Referring to the drawings in detail, 35 wherein like characters of reference denote corresponding parts, the reference character 10 indicates a housing having a removable top or cover 11, upon the under side of which is suspended a motor 12 having a relatively 40 large gear 13 fixed to the armature shaft, not shown, therefor and having its outer free end journaled within a curved arm 14, also suspended from the under side of the removable cover or top 11, and which provides 45 a vertically disposed bearing 15 within its opposite end for journaling the corresponding end portion of a shaft 16 having a worm 17 extending an appreciable distance from an intermediate point of its length and meshing 50 with the gear 13.

Fixed upon the upper free end of the shaft 16 which extends an appreciable distance above the top 11 is a relatively large gear 18 having upwardly extending pins 19 55 arranged at diametrically opposite sides and adjacent the marginal edges thereof.

Journalized within sockets 20 arranged at spaced intervals in the length and upon the under sides of a bracket 21 positioned upon the upper side of the top 11 are the upper 60 end portions of pins 22 held rigidly therein through the instrumentality of set screws 23 while segmental meshing gears 24 are rotatably mounted upon the lower free ends of the pins 22 and have their upper sides separated 65 from the corresponding ends of the sockets 20 by bushings 25 encircling the pins 22 in order that the teeth of the segmental gears 24 will be constantly held in mesh and against canting in eliminating any binding of the gears to insure the operation thereof. The segmental gears 24 further include forwardly inclined slotted portions 26 upon their corresponding inner sides and are of sufficient width and length to readily and 70 easily receive any one of a plurality of the pins 19 arranged upon the upper side of the gear 18 for creating a movement pursuant to moving the gears 24 one toward the other in one simultaneous operation; one of the 75 bushings 25 supporting the segmental gears 24 carries a channel bar 27 and one of the gears 24 in order that the bar 27 may oscillate therewith. Said channel bar 27 includes a clamping member 28 upon its forward end 80 in supporting a shaft 29 having a fan, of any suitable type, as indicated at 30 suspended from its under side. A bifurcated arm 31 is suspended from the under side of the bar and a roller 32 rotatably mounted 85 within its lower free end and adapted to race backward and forward upon an arcuate track 33 arranged upon the upper side of the top 11.

It will thus be noted from the foregoing 95 description and accompanying drawings that when the relatively large gear 13 is set in motion by the source of momentum transmitted by the motor 12, owing to the engagement of the gear 13 with the worm 17 of the 100 gear 16, will in turn cause the gear 18 to rotate in one direction, in the course indicated by the arrow in Figure 1 of the drawings, in order that the vertically disposed pins 19 arranged at diametrically opposite 105 sides thereof will be selectively positioned and engaged within the forwardly inclined slotted portions 26 arranged upon the corresponding and adjacent inner sides of the segmental gears 24 in imparting the necessary oscillatory movement to the channel bar 27 carrying the shaft 29 and fan 30 thereon 110

while the roller 32 tends to support the channel bar 27 upon the track 33. It is generally known that when a motor is left to its own propensities it will attain a great rate 5 of speed and develop undue noises, as in the racing of an engine, and in order to provide suitable means for use in conjunction with the present entitled invention for governing the speed at which the fan 30 may be oscillated, I provide a shaft 34 having its respective ends journaled within the top 11 and an auxiliary bracket 15 suspended from the under side thereof and having its upper end fixed to a gear 36 meshing with the gear 15 18 for imparting the necessary rotary movement to the shaft 34 which in turn has a governing apparatus 37 mounted thereon; the disk 38 carried upon its lower end has its upward vertical movement controlled 20 by a set screw 39 carried upon the inner side of the supporting bracket 35. The housing 10 may obviously include a clamp as indicated at 40 for supporting the device as a whole upon a body or shaft as indicated at 41 25 in Figure 2 of the drawings.

In the use and operation of the present invention it is clearly apparent and manifest that when the motor 12 imparts the necessary rotary movement to the gear 13 fixed 30 to the armature shaft, not shown, it will in turn impart a rotary movement to the shaft 16 owing to its meshing engagement with the worm portion 17 carried thereon and in so doing the gear 18 is rotated to bring the vertically disposed pins 19 arranged upon diametrically opposite sides thereof into selective and continuous engagement within the forwardly inclined slotted portions 26 arranged upon the corresponding inner sides 35 40 of the segmental gears 24 whereby the channel bar 27 will impart the necessary oscillatory movement to the shaft 29 carrying the fan 30, owing to its fixed engagement upon one of the bushings 25 supporting the segmental gears 24.

The relative attainment and rate of speed of the motor is regulated by the governing apparatus, as described and illustrated, whereby the fan 30 and motor mechanism 50 may in no way create a nuisance by the noise attained during the operation of the invention.

The invention is susceptible of various changes in its form, proportions and minor 55 details of construction, and the right is herein reserved to make such changes as properly fall within the scope of the appended claims.

Having described my invention what is 60 claimed is:—

1. A fan comprising a housing, a top therefor, a motor arranged within the housing, a relatively large gear mounted upon the top and operable by said motor, pin 65 members carried upon the face of the gear, a

pair of intermeshing segmental gears including slotted portions mounted upon the top and adapted to selectively receive the pin members therein and a fan carried by one of the second mentioned gears. 70

2. A fan comprising a housing including a top, a motor arranged within the housing, a relatively large gear operable upon said top and connected with said motor, pin members carried at spaced intervals upon upper surfaces of the gear, intermeshing segmental gears mounted upon said top including obliquely disposed slotted portions adapted to selectively receive the pin members of the disk therein to impart oscillatory movement thereto, and a fan carried by one of the segmental gears. 75 80

3. A fan comprising a housing including a top, a motor arranged within the housing, a relatively large gear operable upon said top and connected with said motor, pin members carried at spaced intervals upon upper surfaces of the gear, intermeshing segmental gears mounted upon said top including obliquely disposed slotted portions adapted 85 to selectively receive the pin members of the disk therein to impart oscillatory movement thereto, a fan carried by one of the segmental gears, and means carried by the fan and oscillating across the upper side of the top to assure meshing engagement of 90 said segmental gear. 95

4. A fan comprising a housing including a top, a curved arm suspended from said top within the housing and carrying a 100 motor thereon, a worm shaft journaled upon said arm and operatively connected with said motor, a relatively large gear fixed upon the remaining end of the worm shaft above said top, pin members carried upon diametrically opposite sides of said gear, a pair of intermeshing segmental gears carried by the top and including forwardly extending slotted portions adapted for selective reception of the pin members therein to create 105 an oscillatory movement thereby, and a fan carried by one of said segmental gears. 110

5. A fan comprising a housing including a top, a curved arm suspended from said top within the housing and carrying a motor 115 thereon, a worm shaft journaled upon said arm and operatively connected with said motor, a relatively large gear fixed upon the remaining end of the worm shaft above said top, pin members carried upon diametrically opposite sides of said gear, a pair of intermeshing segmental gears carried by the top and including forwardly extending slotted portions adapted for selective reception of the pin members therein to create an oscillatory movement thereby, a fan carried by 120 one of said segmental gears, and means regulating the speed of the fan oscillations. 125

In testimony whereof I affix my signature.
SAMUEL B. RIAL.
